UNITED STATES PATENT OFFICE.

HARRY DIXSON, OF PELLA, IOWA, ASSIGNOR TO ROLSCREEN COMPANY, OF PELLA, IOWA.

SCREEN HOUSING.

Original application filed May 13, 1925, Serial No. 29,960. Divided and this application filed February 27, 1928. Serial No. 257,272.

The object of my invention is to provide a screen housing and holder of simple, durable and comparatively inexpensive construction.

More particularly it is my object to provide a screen housing adapted to encase a spring roller assembly which in turn is adapted to have screen wound thereon, the housing being formed of a single sheet of material bent to provide four sides with the adjacent edges of the material spaced a slight distance apart for providing the necessary discharge opening through which the screen may be withdrawn.

Still another object is to provide end members adapted to be positioned within the housing proper and spaced from the ends thereof, the end members having out turned flanges which are adapted to rest against the inner surfaces of the walls of the housing and be secured thereto whereby the end members serve to reinforce the entire housing and to retain the edges of the sheet of material forming the housing in proper spaced position.

Still a further object is to provide end members in the housing which are spaced inwardly from the ends of the housing so that the spring roller assembly may be journaled in the end members and project therethrough and yet come within the outline of the housing proper.

Still a further object is to provide circumferentially aligned openings in the walls of the housing and flanges of the end members so that the entire housing and holder may be anchored to a support with fastening means either arranged vertically or horizontally or with fastening means both extending horizontally and vertically.

Still another object is to provide end members which entirely support any screen roller assembly mounted within the housing so that when the entire screen housing and holder is mounted in position, the weight of the screen and the roller assembly is carried by the end members which are directly connected to the support for the entire device.

My present application is a division of my copending application filed May 13, 1925, Serial Number 29,960, the patent number and date of which are 1,680,092, and Aug. 7, 1928.

With these and other objects in view my invention consists in the construction, ar-

angement and combination of the various parts of my device, whereby the objects contemplated are attained, as hereinafter more fully set forth, pointed out in my claims, and illustrated in the accompanying drawings, in which:

Figure 1 is a perspective view of one end of my screen housing and holder.

Figure 2 is a central sectional view through the same with a spring roller assembly and screen or the like mounted therein.

Figure 3 is a sectional view taken on the line 3—3 of Figure 1, illustrating the fastening means arranged in a horizontal position.

In the accompanying drawings I have used the reference character A to indicate generally a sheet of metallic material. The sheet A is bent so as to provide four walls 10, 12, 14 and 16. For the sake of convenience, we will refer to the wall 10 as the bottom; the wall 14 will therefore be the top; the wall 16 will be the back and 12 the front wall of the housing.

The four walls form the housing portion of the entire device. The walls are formed by bending the sheet of material A at right angles whereby a substantially rectangular housing is formed with walls of substantially uniform width.

The two edges of the sheet of material A are spaced a slight distance apart so as to provide a discharge opening 18. The edges of the material of the walls 10 and 16 adjacent the opening 18 are bent over upon themselves so as to provide reinforcing flanges 20 and 22. End members B are placed within the four walls 10, 12, 14 and 16 and engage the inner surfaces thereof.

The end members B are formed of a flat sheet of material 24 having outturned integral marginal flanges 26. The end members B are rectangular in outline and the flanges 26 thereof are spot welded or otherwise secured to the walls of the housing formed of the sheet of material A.

The end members B are positioned inwardly from the ends of the housing proper and the portions 24 form bearing plates in which may be journaled a spring roller assembly C which will be hereinafter more fully set forth. The spring roller assembly comprises a shaft 26 adapted to have its ends extend through bearing openings 28 formed in the end members B as clearly shown in Figures 1 and 2 of

the drawings. The extended ends of the shaft 26 do not project out beyond the ends of the housing proper. A spring 30 is anchored to the shaft 26 at one end and has its other end anchored to a tube like casing 32. Bearings 34 are mounted in the tube 32 and support the tube upon the shaft 26.

A flexible sheet of material 36 such as screen or the like is mounted upon the entire 10 roller assembly and is adapted to be wound thereupon or unwound therefrom. A rod or pin 37 coats with the shaft 26 on the outside of the end member 24 for preventing rotation of the shaft proper.

15 The material 36 may be withdrawn from the housing proper through the opening 18 which extends lengthwise of the housing. It will be noted that the entire spring roller assembly and the material thereon is journaled 20 in the two end members B.

In order to anchor the housing upon a support, I provide aligned openings 38 in the four walls forming the housing which openings register with openings formed in the out-turned flanges 26 of the end members B. The 25 spot welds for connecting the end members B to the four walls are referred to by the reference numeral 40.

30 In the drawings I have shown the openings 38 as being elongated and formed in pairs. Fastening means such as bolts or screws 42 may be employed for anchoring the entire housing to any suitable support such as 44. The fastening means 42 may be arranged 35 horizontally as shown in Figure 3 of the drawings. The same fastening means may be arranged vertically and in that case the fastening means or screws project through the openings 38 formed in the walls 10 and 12 and 40 the flanges 26 resting thereagainst.

45 It will be noted that when the housing is mounted upon a support, that all of the weight of the spring roller assembly and the material mounted thereon is directly supported by the end members B. The end members B prevent to a great extent, possible twisting of the housing proper and maintain the housing in a substantially rectangular cross section at all times.

50 It will be further noted that the elongated openings 38 allow for adjustment of the position where the screws 42 are mounted. It will be noted that the housing and holder are adapted to be fastened to two supports which 55 may vary somewhat in distance and for that reason the elongated openings 38 allow for the slight variation which may be due to contraction and expansion of the parts or window frame to which the device is adapted to 60 be fastened. When the housing and holder rest against two walls that is, against a horizontal surface and a vertical surface, then screws 42 may be used which extend both vertically and horizontally through the same end members. In Figure 2 of the drawings I have

shown the two horizontal screws 42 in cross section and in dotted lines, I have shown one screw arranged vertically which can be accomplished due to the elongated openings 38 even though the openings are aligned circumferentially. 70

One of the advantages of my construction resides in the rigidity which is given to the housing by means of the end members B and their flanges 26. The flanges 26 tend to space 75 the bearing plate 24 inwardly from the end of the housing proper and within this space or recessed opening formed by the end members B, I take care of the projected ends of the shaft 26 and any of the fastening devices 80 which are used for preventing rotation of the shaft or the like.

The fastening screws 42 project through the space of the recessed opening and do not interfere with any of that portion of the 85 housing between the two plates 24. When the device is installed in actual use, the ends of the housing which are formed with the openings 38 may be encased or concealed and the width of the window opening will be substantially the same as the width of the screen 90 mounted in the housing.

Some changes may be made in the construction and arrangement of the parts of my device without departing from the real spirit 95 and purpose of my invention, and it is my intention to cover by my claims, any modified forms of structure or use of mechanical equivalents, which may be reasonably included within their scope. 100

I claim as my invention:

1. A screen housing including a sheet of material bent to form four side walls with the edges of the sheet being spaced a slight distance apart for forming a discharge opening extending lengthwise, end members of rectangular outline adapted to be positioned within the four walls and spaced inwardly from the ends thereof for forming a housing rectangular in cross section with said walls arranged in parallel pairs, said end members including outturned integral marginal flanges adapted to rest against the inner surfaces of said walls and single fastening means adapted to project through either pair of opposite walls for anchoring the housing to a support. 105

2. A screen housing including a sheet of material bent to form four side walls with the edges of the sheet being spaced a slight distance apart for forming a discharge opening extending lengthwise, end members of rectangular outline adapted to be positioned within the four walls and spaced inwardly from the ends thereof, said end members including outturned integral marginal flanges adapted to rest against the inner surfaces of each of said walls, the flanges of said end members being secured to the walls of the housing between which the discharge open- 110 115 120 125 130

ing is formed whereby the edges of said opening are maintained in properly spaced relation to each other and means to project through two of the opposite side walls and 5 the flanges abutting said side walls for anchoring said housing to a support.

3. A screen casing including a sheet of material bent to form four side walls of a length substantially greater than the width with the 10 edges of the sheet being spaced a slight distance apart for forming a discharge opening extending lengthwise, said edges being rebent upon their respective side walls for forming a double thickness at the discharge 15 opening for adding materially to the strength

of said side walls adjacent the opening between the ends of the casing, and end members of rectangular outline adapted to be positioned within the four walls and spaced inwardly from the ends thereof for forming a 20 casing rectangular in cross section with said walls arranged in parallel pairs, said end members including out-turned integral marginal flanges adapted to rest against the inner surfaces of said walls and secured 25 thereto, whereby the casing is prevented from torsional movement.

Des Moines, Iowa, February 15, 1928.

HARRY DIXSON.
